CARPET COVER AND THE LIKE

Samuel R. Goldstein, Baltimore, Md.

Application November 2, 1932, Serial No. 640,880

1 Claim. (Cl. 150—52)

This invention relates to covers for rugs, carpets, curtains, tapestries, draperies, and similar articles of household furnishing.

In many homes it is the practice, during the summer months, to withdraw from use the heavier rugs, carpets, draperies, etc., and utilize others of lighter and more seasonable weight and texture. During the period that the regular articles of furnishing are not being used, it is highly desirable that they be packed and covered for safe keeping during the storage interval, in such a manner that they will be preserved in proper condition and proof against damage and deterioration. To provide suitable covers for use on articles of the character described, (which, for brevity and convenience, will hereinafter be referred to simply as "rugs") is the purpose of this invention.

The principal object of the invention is to provide a rug cover so constructed that a rolled rug may be readily inserted thereinto, snugly contained therein, and easily removed therefrom.

A further object of the invention is to provide a rug cover of this type so constructed as to be moth-proof, dust-proof, moisture-proof, and light-proof.

With these and other objects in view, such as will hereinafter be made manifest, the invention consists, in general, of the structural characteristics, combinations of elements, and arrangement of parts illustrated in the accompanying one sheet of drawings, fully described in the following detailed specification, and specifically pointed out in the appended claim.

35 In the drawing,

Figure 1 is a perspective view of a rug cover constructed in accordance with and embodying the principles of this invention, its parts being shown in closed or rug containing relation.

40 Figure 2 is a similar view of one end of the rug cover shown in Figure 1 but with its parts shown in the open relation to which they would be adjusted during the insertion or removal of a rolled rug.

45 Figure 3 is a perspective view of one end of a rug cover embodying a certain modified form of the invention, and

50 Figures 4, 5, and 6 are top plan views of rug covers embodying certain other modified forms of the invention.

55 Referring, in the first instance, to Figures 1 and 2 of the drawing, there is illustrated a rug cover which is substantially cylindrical in contour and which preferably consists of a flexible body member 10 and two circular end members

11 stitched, cemented, or otherwise suitable secured to the body member.

These members 10 and 11 may be of any desired material but are preferably of textile fabric and the members 11 may be of a heavier material than the member 10 in order to help maintain the parts in proper form and disposition.

Longitudinally extending, in the body member 10 and adjacent an end thereof, is a slot or aperture 12 the edges 13 of which are provided with inwardly projecting tongues 14 of the well known lock-tongue or "zipper" type, the customary reciprocable locking and unlocking member 15 being also provided.

When it is desired to place a rolled rug in a cover such as has just been described, the "zipper" member 15 is actuated to disengage the tongues 14 and permit the aperture 12 to be opened, as shown in Figure 2. The rolled rug is then inserted, longitudinally, into the cover, the near end of the cover is properly adjusted over the corresponding end of the rolled rug, and the "zipper" member 15 is then actuated to engage and lock the tongues 14, effectively closing the aperture 12, as shown in Figure 1.

In some cases, where the covered rug may be subjected to rough or careless handling, and there is danger that the "zipper" member 15 may be accidentally actuated to open or partly open the aperture 12, a protective flap 16 may be provided for the "zipper" parts and construction, as shown in Figure 3. This flap is preferably of the same material as the body member 10 and is to be stitched, cemented or otherwise secured to the member 10 along one of its longitudinal edges, as indicated at 17, and adjacent and parallel to the aperture 12, and may have its other edge provided with a series of snap-buttons 18 or other suitable releasable retaining means, so that, when the aperture in the cover is closed, the "zipper" parts may be completely covered, as shown, and their casual or accidental release prevented.

In Figure 4 is illustrated a modified form of the invention wherein a "zipper" equipped aperture 12A is provided in the body member 10 and extends substantially from end to end thereof. In this form, the cover is adapted to be opened from one end to the other for lateral insertion or removal of the rolled rug.

In Figure 5 is illustrated another modified form of the invention wherein the body of the cover is formed of two longitudinally separable members 10A, their meeting edges 19 being equipped with that form of "zipper" construction which permits

of complete union or total separation of the two engageable elements. In this form, the two halves of the cover are longitudinally applied to or removed from the rolled rug over its ends, and the "zipper" parts serve to unite them when the cover is in place.

In Figure 6 is illustrated yet another modified form of the invention wherein a transverse rug insertion and removal aperture 12B is provided 10 in the body member 10 closely adjacent an end thereof. This aperture 12B is provided with the necessary "zipper" parts and extends almost but not completely around the member 10. A small interval 20 occurs between the ends of the aperture 12B and this portion of the web of the body member 10 serves as a hinge which permits the end portion of the cover to be swung aside when a rolled rug is to be inserted or removed.

It is, of course, obvious that each of the forms 20 illustrated in Figures 4, 5, and 6 may be provided with protection flaps similar to that shown in Figure 3, if it is so desired.

Other modifications in form and structure will 25 readily suggest themselves to those skilled in the art and it is to be understood that all such are contemplated as being a part of this invention insofar as they fall within the scope of the appended claim.

While the material of which the cover is made 30 may be of any suitable flexible or semi-flexible character, it is greatly to be preferred that it be a textile fabric and of such a close and tightly woven nature as to be moth-proof, dust-proof, moisture-proof, and light-proof.

The moth-proof feature may, if desired, be strengthened or augmented by treating the fabric with a solution of tetrachloro-rotenzol or other chemical substance objectionable to moths.

Similarly, the moisture-proof feature may, if 5 desired, be strengthened or augmented by subjecting the fabric to a rubberizing or other similar process or treatment.

Thus it will be seen that there has been provided a rug cover which is simple in structure, 10 economical to manufacture, easy to use, and highly efficient for the purpose intended.

As before pointed out, the term "rug" is used throughout this specification and will hereinafter be similarly used in the appended claim, in a 15 purely generic sense. It is in no way to be taken as an intended or implied restriction or limitation upon the scope of the invention but must be understood as including not only rugs, per se, but carpets as well, and all other articles of household 20 furnishing which may be rolled and covered for safe keeping and storage.

I claim:

A rug cover of the class described comprising two flexible cylindrical body members, members 25 for closing one end of each body member, zipper means only for securing and holding the two body members together, said zipper means so arranged that the zipper can be actuated to permit complete separation of the two body members, and flexible 30 means secured to one of the body members for covering the zipper means to prevent accidental release of the zipper.

SAMUEL R. GOLDSTEIN.
